GRADUATING AND MEASURING DEVICE
FOR SHOE LASTSHenry G. Clausing, Portsmouth, Ohio, assignor
to Vulcan Corporation, Portsmouth, Ohio

Application December 19, 1946, Serial No. 717,131

5 Claims. (Cl. 33—3)

1

The present invention relates to improvements in grading and measuring devices for shoe last inspection and is particularly directed to a device for making a reference mark at a predetermined point on the instep of all sizes of lasts in a particular lot so that other inspection measurements may be made on each last with the mark as the initial starting point.

Shoe lasts are employed by the shoe manufacturer as a form on which certain shoe manufacturing steps are carried out. The shoe lasts are inserted into the unfinished shoe uppers preliminary to the sole attaching operation. These lasts must therefore be of every conceivable style and size and are generally custom made on the shoe manufacturer's order. Furthermore the last must exactly conform to standard sizes of the shoes to be made thereon and to this end a number of measurements must be taken on them from a known reference point by both the last manufacturer and the shoemaker to determine their size, length, cross-sectional contours and other dimensions so that exact last sizes are maintained.

It has generally been the practice to locate the last reference point at the uppermost point of the last instep, said point incidentally lying at the approximate center of the longitudinal dimension of each shoe last. A great number of last sizes are made from a single master last of a certain style and model by adjusting the mechanism of the last copying lathe to form lasts proportionally longer or shorter, and wider or narrower than the master last. However the position of the reference point may vary slightly between lasts made from master lasts having different styles and models, for instance, the central reference point in lasts for making women's shoe styles would tend to be off center in the direction of the heel portion whilst lasts for very low heeled men's style shoes may tend to be off-center in the direction of the toe portion. It is therefore a particular object of the present invention to provide a measuring device for lasts which facilitates the grading of said lasts in lot sizes and provides a definite and standard reference point for lot sizes from which the manufacturer of the last may work and which provides a reliable means for last inspection by the manufacturer and the purchaser thereof.

Another object of the present invention is to provide a last grading and measuring device which may be quickly adjusted and set for determining the longitudinal centers of all lot sizes of shoe lasts made from a master model last of a certain

2

style, whereby inspection steps for the entire lot are greatly facilitated and the results more accurately determined.

Another object of the invention is to provide a device which may be readily adjusted by the shoemaker in accordance with the last manufacturer's instructions so that an entire last lot may be graded in a quick and efficient manner.

A still further object of the invention is to provide a last measuring device which has a rugged construction, is readily operated and on which last measurements can be made in a quick and efficient manner.

Other objects will be apparent from the following specification and drawings wherein:

Fig. 1 is a top plan view of the last grading and measuring device.

Fig. 2 is a side elevation of the device with a last to be measured illustrated in operative position therein.

Fig. 3 is an enlarged cross-sectional view taken on line 3—3 of Fig. 2.

Fig. 4 is an enlarged cross-sectional view taken on line 4—4 of Fig. 2.

Fig. 5 is a fragmental cross-sectional view taken on line 5—5 of Fig. 3.

With reference to the drawings the numeral 6 indicates an elongate base for my measuring device which has formed therein a pair of longitudinally extending grooves 7 and 8 each disposed on opposite sides of the longitudinal center line of the base. As indicated in Fig. 3 a central ridge 9 is formed between the grooves and a longitudinal rule 10 is secured thereto by screws 11. A cross-head 12 is fixed to one end of the base 6 by screws 13 said cross-head having a vertical last contacting face 14 on its interior side which is at right angles to the rule and in the transverse plane of the zero calibrations marked on the upper edge 15 of the rule which is graduated in inches. The face 14 also serves as the zero reference plane for the linear calibrations on the lower longitudinal edge 16 of the rule which is graduated in shoe sizes from size zero to size 13 for infant's and children's shoes, and from size 1 to size 17 for women's and men's shoes. It will be noted that the divisions made by the calibrations of the scale along edge 16 have identical longitudinal dimensions and are consecutively graduated in last sizes, each last size division being equal to $\frac{1}{3}$ of an inch on the linear scale along edge 15.

A sliding cross-head 17 is mounted on the base for longitudinal movement said cross-head having a last contacting face 18 lying in a vertical

plane at right angles to the rule. The cross-head 17 is provided with a pair of spaced runners 19 and 20 which slide in grooves 7 and 8 respectively said runners having formed in their interior sides opposed slots 21 and 22 for slidably receiving between them the edges 15 and 16 of the rule (Fig. 3). The cross-head is also provided with a centrally disposed longitudinal groove 23 (Fig. 6) in which a strip of spring metal 24 is mounted, said strip having a bent portion 25 at one end which is anchored in an inset 26 in the groove whilst the opposed end is free to move longitudinally along the top surface of said groove. The cross-head 17 is precluded from sliding off the rule by means of a stop which takes the form of a screw 27 threaded in the base and having an enlarged head for engaging the rear edge of the cross-head.

A last center indicator bar 28 is mounted on the base for axial movement in a direction parallel to the rule 10 and is held thereon between the fixed cross-head 12 and a standard 29 secured to the base by a screw 30. As indicated in Fig. 3 the indicator bar is substantially square in cross-section and is slidably mounted in the upper end of the standard 29 by a cap 31 secured thereto by screws 310 and which has formed on its inner surface a tapered groove 32 that cooperates with a tapered groove 33 formed in the standard to form a square aperture for snugly receiving the bar 28. A similar indicator bar receiving opening is formed between a cap 34 and the upper edge of the cross-head 12, a wing nut 35 being adapted to cooperate with a threaded shaft 36 anchored in the cross-head for locking the cap 34 against the bar when said bar has been longitudinally adjusted to a predetermined position.

A sliding block 37 is provided with a longitudinal aperture 38 for slidably receiving the bar 28, said bar having two upstanding arms 39 and 40 between which is pivoted a marker 41. The marker arm is secured to the block by a pivot pin 42 threaded in aligned apertures formed in the arms 39 and 40, said pin being locked by a set nut 43. The free end of the marker is provided with a downturned pointed end 44 and a finger engaging disc 45 so that it may be pressed downwardly into a last resting upon the base. The block may be adjustably secured in the desired longitudinal position by a set screw 46 (Fig. 4) which is threaded in the block and engages a bronze washer 47 which in turn bears against a corner of a bar when the said screw is tightened.

As indicated in Figs. 1 and 2 the indicator bar has a number of calibrations formed on one surface which are as a group, disposed substantially centrally of the extremities of the rule 10 and the calibrations thereon. It will also be noted that these calibrations are equally graduated in alternate last sizes and that each division has a linear dimension equal to each unitary last size division on the rule 10. The bar is therefore graduated in one-half last sizes which will be apparent by a comparison of these calibrations with the ones on the longitudinal edge 16 of the rule 10.

Certain uses to which my device may be put in obtaining measurements of and grading of finished lasts will now be described to clearly indicate its utility and the novel functions of the various parts thereof, and to this end, the method of adjusting my device to place an instep reference mark on lasts of a particular lot, will now be set forth. It will be noted with reference to Fig. 2, that a last 48 from a certain lot to be inspected

is placed upon the base with its longitudinal axis substantially parallel with the rule 10. One end of the last is in contact with the face 14 of the fixed cross-head 12 whilst the sliding cross-head 17 is moved inwardly until its face 18 contacts the opposed end of the last. Readings are then taken on the linear scale on the upper edge 15 and the last size scale on the lower edge 16 of the rule 10 by sighting along the plane of the contacting surface 18 of the sliding cross-head. In the example illustrated in Figs. 1 and 2 the reading on the linear scale would be 9 $\frac{3}{4}$ inches whilst the last scale would show a No. 4 $\frac{1}{2}$ size for women or men. Said linear reading is then divided by two to obtain half the longitudinal measurement of the last. The last is then removed from the device and the sliding crosshead 17 is moved inwardly until the linear scale indicates one-half of the longitudinal measurement obtained from the linear scale. In the case illustrated said number would be 4 $\frac{7}{8}$ inches. The block 37 is then slid on the bar 28 until the left hand face thereof registers with the calibration line beside the number 4 $\frac{1}{2}$ on the bar which is the last size obtained for the linear measurement of 9 $\frac{3}{4}$ inches. The sliding block is then clamped at said position by turning up on the set screw 46. The thumb nut 35 is loosened, and the bar 28 with block 37 clamped thereto is moved axially until the pointer 44 coincides with the face 18 of the sliding crosshead 17. The bar is then clamped in position by operation of the wing nut 35, and the bar is then in the proper position to make a reference mark on the identical instep portions for all lot sizes of lasts made from a particular master model last. The remaining last sizes of the lot may be marked with a measurement reference point by allowing the block 37 to slide freely on the bar and merely placing a last between the cross-heads to obtain the exact last size, taking a reading of the last size on the scale along the lower edge 16 of the rule, and then moving the block 37 to the indicated last size on the bar. The lever 41 may then be operated to make a reference mark on the lasts of said size so that other inspection measurements may be made therefrom. It will be therefore noted that all sizes of lasts from a particular lot may be quickly and readily inspected by the use of this instrument for inspection by the purchaser and that a manufacturer may also give a last certain measurements with the use of my device which may be readily transmitted and checked by the purchaser upon a similar device. This device may also be readily adjusted to other styles and models of master lasts by axially adjusting the bar to register the upper point of the instep on all sizes of said styles.

What is claimed is:

1. In a device of the character described the combination of a base, a fixed cross-head on the base, a rule secured to the base and disposed thereon at right angles to the fixed cross-head, a sliding cross-head mounted for rectilinear movement parallel to the rule, a last center indicator bar mounted on the base for axial movement and disposed parallel to the rule, means for locking the bar in a predetermined longitudinal position, a block slidably mounted on the bar, means for locking the block on the bar at a predetermined position, and a marker pivotally mounted on the block for movement in a vertical plane parallel to the cross-head.
2. In a device of the class described the combination of a base, an elongate rule secured to the

base, a fixed cross-head on the base having a vertical last contacting surface disposed at right angles to the rule, a sliding cross-head mounted for rectilinear movement on the base in a direction parallel to the rule, said sliding cross-head having a vertical last contacting face disposed in a plane parallel to the face of the fixed cross-head, a last center indicator bar positioned parallel to the rule and mounted on the base for axial movement, means for locking the bar at a predetermined position on the base, a block slidably mounted on the bar, means for locking the block at a predetermined position on the bar, and a marker pivotally mounted on the block for movement in a vertical plane parallel to and intermediate the contacting faces of the cross-heads.

3. In a device of the character described the combination of a base, an elongate rule secured to the base having calibrations thereon graduated in linear divisions indicative of consecutive last sizes, a fixed cross-head on the base having a vertical last contacting surface disposed at right angles to the rule, a sliding cross-head mounted for rectilinear movement on the base in a direction parallel to the rule, said sliding cross-head having a vertical last contacting face disposed in a plane parallel to the face of the fixed cross-head, a last center indicator bar positioned parallel to the rule and mounted on the base for axial movement, said bar having consecutive last size calibrations on its face disposed substantially centrally of the calibrations on the rule and each size graduated in linear divisions half the length of the linear divisions on the rule, means for locking the bar at a predetermined position on the base, a block slidably mounted on the bar, means for locking the block at a predetermined position on the bar, and a marker pivotally mounted on the block for movement in a vertical plane parallel to, and intermediate the, contacting faces of the cross-heads.

4. In a device of the character described the combination of a base, an elongate rule secured to the base having observable calibrations thereon graduated to indicate last sizes, a fixed cross-head on the base having a vertical last contacting surface disposed across and at right angles to the rule and adapted to serve as a zero reference surface for said rule, a sliding cross-head mounted for rectilinear movement on the rule and having a vertical last contacting face lying in a plane parallel to the face of the fixed cross-head, a standard spaced transversely from the rule and mounted upon the base intermediate its length, a last center indicator bar mounted on the standard and the fixed cross-head for

axial movement in a direction parallel to the rule, said bar having consecutive last size calibrations on its face disposed substantially centrally with reference to the calibrations on the rule and each last size calibration on the bar graduated in equal linear divisions half the length of each linear division for the corresponding last size on the rule, means for locking the bar in a predetermined position on the base, a block slidably mounted on the bar, means for locking the block on the bar at a predetermined position relative to the rule, a marker arm pivotally mounted on the block for movement in a vertical plane parallel to and intermediate the contacting faces of the cross-heads, and a pointed end on the marker arm movable into a position directly above the rule upon pivotal movement of said arm.

5. In a device of the character described the combination with a base, a calibrated rule on the base, and a pair of cross-heads mounted on the base for relative movement adjacent to the rule, of a standard spaced transversely from the rule and mounted upon the base intermediate its length, a last center indicator bar mounted on the standard and the fixed cross-head for axial movement in a direction parallel to the rule, said bar having consecutive last size calibrations on its face disposed substantially centrally with reference to the calibrations on the rule and each last size calibration on the bar graduated in equal linear divisions half the length of each linear division for the corresponding last size on the rule, means for locking the bar in a predetermined position on the base, a block slidably mounted on the bar, means for locking the block on the bar at a predetermined position relative to the rule, a marker arm pivotally mounted on the block for movement in a vertical plane parallel to and intermediate the contacting faces of the cross-heads, and a pointed end on the marker arm movable into a position directly above the rule upon pivotal movement of said arm.
